Application filed May 10, 1894. Serial No. 510,803. Term of patent 3½ years.

To all whom it may concern:

Be it known that I, LOTHAR VON GRAVE, a subject of the Emperor of Germany, residing at Wallingford, New Haven county, State of Connecticut, have invented and produced a new and original Design for Frames for Pictures, Mirrors, and the Like, of which the following is a specification, reference being had to the accompanying drawing, which shows a face view of a frame illustrating my design, one-half being shown in full lines and the remainder in outline.

The essential characteristics of my design consist of a central rectangular ornamental portion having an opening therein; an open-work leaf-like border surrounding and following the contour of the central rectangular portion, and an open-work leaf-like base ex-

tending from and having portions thereof continuous with portions of said openwork border. 20

In the drawing, *a* represents a central rectangular ornamental portion provided with an opening *b* therein. Surrounding and following the contour of this rectangular portion *a* is an openwork leaf-like border *c*, extending 25 from which is a leaf-like base *d*, portions thereof being continuous with portions of the openwork border, as shown at *e f*.

What I claim is—

The design for frames for pictures, mirrors, 30 and the like, substantially as shown and described.
